STANCHION

Filed Oct. 9, 1924

2 Sheets-Sheet 2

UNITED STATES PATENT OFFICE.

WILLIAM F. PLANTIKO, OF STEVENS POINT, WISCONSIN, ASSIGNOR TO FARMERS' BARN EQUIPMENT COMPANY, OF STEVENS POINT, WISCONSIN, A CORPORATION OF WISCONSIN.

STANCHION.

Application filed October 9, 1924. Serial No. 742,596.

To all whom it may concern:

Be it known that I, WILLIAM F. PLANTIKO, a citizen of the United States, and resident of Stevens Point, in the county of Portage and State of Wisconsin, have invented certain new and useful Improvements in Stanchions; and I do hereby declare that the following is a full, clear, and exact description thereof.

10 This invention relates to cattle stanchions.

This invention is an improvement over that disclosed in my United States Patent Number 1,200,231, dated October 3, 1916 for cattle stanchions and has in general the same 15 objects as those disclosed in such patent in addition to the objects enumerated hereafter.

Further objects are to provide an improved stanchion in which the sure stop or 20 stop bar construction is materially simplified, and in which a stronger and more easily and quickly assembled mechanism is provided, and in which a small number of parts are employed for operating and controlling the sure stop bars.

Further objects are to provide an improved stanchion hanger and alignment device which is adapted to cooperate with the usual stanchion equipment in a manner to 30 permit the easy and ready adjustment of the stanchion so as to align long or short cows with the rear gutter, and to provide a stanchion hanger in which bolts and nuts are wholly avoided, and an extremely simple and easy operating device is provided.

An embodiment of the invention is shown in the accompanying drawings, in which:

Figure 1 is a view showing the stanchion open.

40 Figure 2 is a similar view showing it in closed position.

Figure 3 is an enlarged partial sectional view on the line 3-3 of Figure 1.

Figure 4 is an enlarged transverse view 45 showing the stanchion hanger.

Figure 5 is a horizontal sectional view on the line 5-5 of Figure 4.

The stanchion comprises the usual uprights 1 which are preferably of tubular construction and which support the top rail 2 and the control bar 3, such control bar being operated by means of the hand lever 4 in any suitable manner as for example as shown in my above noted patent.

The neck bars 5 and 6 are pivoted at 55 their lower ends to a fitting 7 which is adjustable longitudinally of the stall in any suitable manner, as disclosed for instance in my above noted patent. The upper ends of these neck bars are suspended and supported by an open ended casing 8, the movement of the neck bars being controlled in any suitable manner, for instance as described in my above noted patent.

A relatively long stop bar 9 has its upper 60 end pivoted to a clip 10 secured to the control bar 3 and has its lower end pivoted to a lever 11. This lever 11 is pivoted to a bracket 12 clamped to the upright 1, as shown in Figures 1 and 2.

70 It is to be noted that the end of the lever to which the stop bar 9 is pivoted is relatively short and that the lever projects a materially greater distance on the other side of its pivot point, and carries an apertured casting 13. This apertured casting slidably receives the short stop bar 14 whose upper end is pivotally carried by means of a bracket 15 bolted to the upright 1.

75 It will be seen that when the control bar 3 is moved to stanchion closing position that the long stop bar 9 will be rocked into substantially vertical position, as shown in Figure 2, and will depress the right hand end of the lever 11 thus sliding the collar or casting upwardly on the short stop bar 14 and rocking such short stop bar into proximity to the upright 1, as shown in Figure 2.

80 This structure may be duplicated on opposite sides of the intermediate stanchion. However, at the end stanchion as shown in Figures 1 and 2, a single long stop bar 9' is pivotally carried by means of a short link 11' secured to a bracket 12' attached to the other upright 1. The upper end of the bar 9' is operatively coupled to the control bar 3 by means of a clamp 10'. This construction may be employed on one side of intermediate stanchions if desired.

85 It is to be particularly noted that the lever 11 is of extremely simple construction and provides for easy attachment to the collar or casting 13 and to the lower end of the long stop bar 9. This construction is 95 illustrated in detail in Figure 3 from which it will be seen that such lever is composed of two similar members 16 which are ribbed

and flanged, as shown. These members are each provided with inwardly projecting lugs 17 which fit within an aperture formed in the bracket 12. The long ends of the members 16 are apertured and receive the hooked trunnions 18 of the collar 13. A bolt 19 is passed through the short ends of the members 16 and passes through the lower end of the long stop bar 9. This bolt 10 is the only securing means that is necessary to hold the members 16 in their correct position and to permit their ready attachment and detachment from the collar 13, the bracket 12 and the lever 9.

15 In order to permit the ready aligning of a short or long cow with the rear gutter suitable means are provided for adjustably holding the member 8 (see Figures 1, 2 and 4) in its correct position and providing for 20 forward and rear adjustment of such member. This structure, as shown in Figure 4, may comprise a roughly rectangular suspension member having an upper transverse portion 20 and a lower transverse portion 21. The upper transverse portion is clamped to the angle bar 2 (see Figures 1, 2 and 4) by means of a V-shaped clamp 22 whose projecting ears are secured by means of bolts 23 to the transverse member 20. 30 If desired, this transverse member may be provided with an upwardly bulged central portion 24 to fit within the channel of the angle bar 2, as shown in Figure 4.

The lower transverse member 21 is provided with a plurality of apertures 25 through any one of which the projecting pin 26 may extend. This pin is provided with a head 27 which swivelly fits and suspends the hanger or open ended casing 8, 40 as shown in Figure 4. A transverse aperture 28 extends through the pin 26 and a locking key 29 is passed through such aperture and retains the pin in its correct position. This locking key 29 is preferably a 45 rod and is provided with a right angle downwardly extending portion 30 which terminates in a horizontally extending tongue 31.

In using the suspension device, the pin 26 is inserted in the appropriate aperture 25 to secure the desired alignment of the cow with the rear gutter. Thereafter, the key 29 is slipped through the transverse aperture 28 of the pin 26 and its end is dropped 55 downwardly through the adjacent aperture 25, and its tongue 31 is hooked beneath the transverse member 21.

It will be seen therefore that a suspension device has been provided which is adjustable to insure the proper aligning of the cow with the rear gutter, and which is so constructed that it does not require the unscrewing or removal of nuts or bolts for its adjustment.

65 This construction, therefore, provides an

extremely simple locking and suspension means for the adjustable hanger and may be easily operated without the use of tools.

It will further be seen that a very simple and strong stop bar construction has been 70 provided in which a very small number of parts are needed, in which the assembling and dismantling may be most easily effected, and in which the utmost reliability is attained.

75 Although the invention has been described in considerable detail, it is to be understood that the invention may be variously embodied and is, therefore, to be limited only as claimed.

I claim:

1. A stanchion comprising a pair of uprights, a pair of neck bars suspended therebetween, a control bar for operating said neck bars and slidably carried by said uprights, a long stop bar located upon the outer side of one of said uprights and having its upper end pivoted to said control bar, a lever pivoted intermediate its ends to said upright and having one end pivoted to the lower end 80 of said stop bar and having an inner end provided with a pair of apertured ears, a collar having a pair of outwardly projecting trunnions fitted within the apertures of said ears, and a second stop bar located on the inner side of said upright and having its lower portion slidably fitted within said collar.

2. A stanchion comprising a pair of uprights, a pair of neck bars suspended therebetween, a control bar for operating said neck bars and slidably carried by said uprights, a long stop bar located upon the outer side of one of said uprights and having its upper end pivoted to said control bar, a lever pivoted intermediate its ends to said upright and having one end pivoted to the lower end of said stop bar and having an inner end provided with a pair of apertured ears, a collar having a pair of outwardly projecting trunnions provided with hooked ends and fitted within the apertures of said ears, and a second stop bar located on the inner side of said upright and having its lower portion slidably fitted within said collar, said lever having two portions normally held together by a bolt forming one of the pivotal connections.

3. In a stanchion the combination of a 120 slidable control bar, an upright, a long stop bar located upon one side of said upright and having its upper end operatively coupled to said control bar, an apertured bracket secured to said upright adjacent its lower end, a lever having complementary parts 125 provided with inwardly extended integral trunnions fitting the aperture in said bracket, a bolt passing through one end of said lever and through the lower end of said stop bar, said lever having apertured ears adjacent its 130

other end, a collar provided with trunnions fitted within said apertured ears and having hooked ends, and a short stop bar located upon the other side of said upright, pivotally 5 carried at its upper end by said upright, and having a free lower end slidably fitting said collar.

4. In a stanchion the combination of a top bar having an angular upper portion, 10 a rectangular supporting frame positioned below said top bar, a bracket having an inverted V-shaped portion bolted to said frame and fitting over said top bar, said frame having a transverse lower portion provided with 15 a plurality of apertures, a pair of neck bars, a suspension therefor, a pin carried by said suspension and provided with a laterally extending aperture adjacent its upper end, said pin being adapted for positioning within 20 anyone of the apertures in said transverse member, and a locking key adapted to enter the aperture in said pin and having a hooked end adapted to be positioned in one of the 25 apertures in said transverse member, whereby the neck bars may be adjusted.

5. In a stanchion the combination of a top bar, a rectangular frame carried thereby, and having a transverse lower portion provided with a plurality of apertures, a pin adapted 30 to fit any of said apertures and provided with an aperture extending transversely through its upper portion, a locking key

adapted to fit said transversely extending aperture and having right angle extensions provided with an outwardly projecting tongue, said extension and tongue being adapted for passage through any one of said apertures in said transverse member, and said tongue being adapted to hook beneath said transverse member, and a pair 40 of neck bars suspended from said pin.

6. In a stanchion the combination of a top bar, a rectangular frame carried thereby, and having a transverse lower portion provided with a plurality of apertures, a pin 45 adapted to fit any of said apertures and provided with an aperture extending transversely through its upper portion, a locking key adapted to fit said transversely extending aperture and having right angle extensions provided with an outwardly projecting tongue, said extension and tongue being adapted for passage through any one of said apertures in said transverse member, and said tongue being adapted to hook beneath 50 said transverse member, a housing swivelly carried by said pin, and a pair of neck bars carried by said housing.

In testimony that I claim the foregoing I have hereunto set my hand at Stevens 60 Point, in the county of Portage and State of Wisconsin.

WILLIAM F. PLANTIKO.
